CLAMPING DEVICE FOR ELECTRON TUBES
AND THE LIKEArthur Chiger, New York, N. Y., assignor to Times
Facsimile Corporation, New York, N. Y., a corporation of New York

Application June 23, 1947, Serial No. 756,360

3 Claims. (Cl. 248—361)

1

This invention relates to clamping devices and more especially it relates to devices for clamping in place, replaceable electric units of the plug-in type.

A principal object of the invention is to provide an improved and simplified clamp for holding electron tubes and the like in their plug-in sockets, so that they are incapable of being loosened by excessive jars or vibrations.

A feature of the invention relates to a clamp which is so constructed that such devices as electron tubes can be readily replaced and clamped in their socket receptacles without requiring special tools such as wrenches or screw-drivers to release the clamp.

Another feature relates to an electron tube clamp which can be slidably adjusted in a vertical direction and locked in a definite vertical position without the use of thumb screws, set screws, or the like, which tend to become loose after continued vibration of the parts.

A further feature relates to a multiple electron tube clamp which can be locked in vertically-adjusted position and at any desired horizontal angular position with respect to a pedestal support, and without using set screws or the like.

A still further feature relates to the novel organization, arrangement and relative location of parts which cooperate to provide an improved electron tube clamp.

Other features and advantages not specifically enumerated will be apparent after a consideration of the following detailed descriptions and the appended claims.

In the drawings which show, by way of example, certain preferred embodiments,

Fig. 1 is a top plan view of a duplex electron tube clamp according to the invention.

Fig. 2 is a front view of the duplex clamp of Fig. 1.

Fig. 3 is a view of a single clamp corresponding to that of Fig. 1.

Fig. 4 is a modification of Fig. 3.

In Fig. 2 of the drawings, there are shown, by way of example, two typical electron tubes 10, 11 which carry the usual base members 12, 13 and the usual plug-in prongs 14, 15. In the conventional way, the tubes are plugged-in to the usual contact receptacles or sockets 16, 17 which are carried or mounted in the chassis 18 of the radio set or similar apparatus. In order that the tubes can be readily inserted and removed as necessary, the sockets 16 are usually of the spring-contact type which frictionally engage the contact pins 14, 15. However it very frequently

2

happens that under unusual vibratory conditions the tubes may become loose in their sockets, thus preventing the making of proper circuit contact between the tube and the socket springs.

Various expedients have been proposed heretofore for locking the tubes in their sockets. However these prior expedients have, in the main, been comparatively complicated and usually have required the use of set screws or thumb screws for locking the adjustable clamp member in position. Here again the set screws or thumb screws also may become loose after continued vibration, thus destroying the effectiveness of the clamp. Furthermore with such set-screw clamps, it is necessary to have available a wrench or screw-driver for the purpose of loosening or tightening the clamp when a tube is to be inserted or removed from its socket.

Furthermore, with such set screw devices, in order that the set screw may be properly fastened, it is usually necessary to provide a flat or key way against which the set screw can be tightened. This necessarily restricts the angular position of the clamping member around the support by which it is carried. The present invention provides an arrangement which overcomes the disadvantages of the usual set screw type of clamp. In accordance with the invention, the clamp comprises in general a pedestal or rod 19

which is arranged to be fastened in any suitable manner, for example by the fastening nuts 20, 21 to the chassis 18. If desired, the rod 19 can be riveted or permanently attached to the chassis 18. In any event, it is fastened to the chassis at a point adjacent to the tube to be clamped. In those cases where two tubes are located adjacent to each other, and as illustrated in Fig. 2, the rod 19 can be attached to the chassis 18 at a point mid-way between the tube sockets.

The clamping member proper comprises a sheet metal strip 22 which terminates at its ends in two integral annular members 23, 24, each annular member having a struck-up inclined lip 25, 26 which is of slightly smaller inside diameter than the diameters of the tops of the tubes 10 and 11, so that the top of each tube fits snugly within the corresponding annular opening of members 23 and 24. The usual radio tube has a rounded top or dome, the periphery of which is engaged by the lip 25 or 26, when the member 22 is lowered into contact with the said dome. The yoke portion 27 of the member 22 has a central opening which is of very slightly greater diameter than that of the rod 19 so as to permit the member 22 and its clamping rings 23, 24 to be

readily adjusted in a vertical direction along the rod 19. However, in order to lock the member 22 in its adjusted position, the said member has integrally fastened to the yoke portion 27 thereof a U-shaped locking member 28, the horizontal arm 29 of which is welded or otherwise integrally fastened to the member 22, the other arm 30 being normally inclined with respect to arm 29. The arms 29 and 30 have openings which are just slightly larger than the diameter of the rod 19. The plane of the opening in arm 30, instead of being perpendicular to rod 19, is inclined, and since this opening is only very slightly larger than the diameter of rod 19, and because of the springy nature of the member 28, the left-hand edge of the opening bites into the said rod and firmly holds the clamp in its adjusted position. The member 28 can be provided with oppositely extending integral gripping lugs 31, 32 to facilitate release of the clamp.

When it is desired to release the clamp, all that is necessary is to press upwardly, as indicated by the arrow, against the lugs 31, 32. This pressure frees the edge of the opening in arm 30 from the rod 19 so that the clamp is free to slide vertically on the rod 19. If desired, the surface of rod 19 may be slightly roughened. When the clamp has been adjusted to the desired position, it is merely necessary to release the upward pressure on the lugs 31, 32, with the result that arm 30 again springs back to its normal position where it tightly engages the rod 19.

From the foregoing, it will be seen that the clamp 22 can be used in any desired angular relation around the rod 19, depending upon the location of the tubes 10, 11. Preferably, the member 22 is of sheet metal stock having sufficient springiness so that when the clamp is locked against the tubes, a somewhat resilient pressure is applied against the tubes.

It will be understood, of course, that while Figs. 1 and 2 show a clamp of the duplex type for simultaneously clamping two tubes, that the member 22 may carry three or more annular members similar to members 23 and 24, depending upon the number of tubes which are to be clamped.

It will also be understood that if desired, a single clamping member may be provided. Such an arrangement is shown in Fig. 3 wherein the member 28a which corresponds to member 28 (Fig. 2) is formed as an integral piece with the retainer ring 24a. Thus as shown in Fig. 3, the parts 24a and 28a can be punched from a single metal strip with the portion 28a bent back upon itself to form the U-shaped clamping member. However, in this case both the arms 29a and 30a are normally inclined with respect to the rod 19 so that the right-hand edges of the openings in both of the arms 29a and 30a bite into the rod 19.

To provide an easier manipulation of the clamp for releasing and locking purposes, it may be made of the form shown in Fig. 4. In this embodiment, the clamp is made from a single spring metal blank provided with a punched-out retainer ring portion 24b. The rest of this blank is bent back upon itself as indicated by the numerals 33, 34, to form a double thickness of metal, which double thickness is perforated to receive the rod 19. The metal blank is again bent back upon itself in the reverse direction to form the

U-shaped portion 28a also having an opening to receive the rod 19. Preferably the end 35 of the blank extends beyond the bent back portions 33 and 34 to provide an easy grip. When it is desired to release the clamp of Fig. 4, it is merely necessary to grip the portions 33 and 35 between the fingers to bring the portion 35 substantially perpendicular to the rod 19, whereupon the clamp is free for sliding movement on the said rod.

While certain particular embodiments have been disclosed herein, it will be understood that changes and modifications may be made therein without departing from the spirit and scope of the invention.

What is claimed is:

1. A clamp for electron tubes and the like, comprising a single metal blank having an annular means defining a punched-out opening to register against the top of the electron tube to be clamped, and having a flexible strip portion which is bent back upon itself to substantially U-shape, the arms of the U having aligned openings, a rod passing through said openings, at least one of the arms of said U being normally inclined with respect to the rod to cause the edge of the opening therein to tightly engage the surface of said rod.

2. A duplex clamp for clamping a plurality of radio tubes in their respective sockets, said clamp comprising a metal strip having annular end portions each adapted respectively to engage the top of an electron tube, a yoke portion joining said annular portions, a rigid rod anchored at its lower end between said tubes to the common support for said tubes, said yoke portion having an opening to receive the upper end of said rod, a U-shaped spring metal strip carried by said yoke portion with the arms of the U having respective openings also to receive said rod, one of the arms of the U being normally inclined with respect to the rod to grip it tightly and adapted to be bent towards the opposing arm of the U to release said tight engagement.

3. A clamp for an electron tube and the like, comprising a rod arranged to be fastened at its lower end to a fixed support which also supports the tube to be clamped, a tube clamping member having a portion extending outwardly from said rod and arranged to receive and abut against the upper end of said tube to be clamped, said member having a flexible strip extending from the marginal portion thereof and bent back upon itself to substantially U-shape, the arms of the U having aligned openings through which the upper end of said rod passes, at least one of the arms of said U being normally inclined with respect to the rod to cause the edge of the opening therein to tightly engage the surface of said rod, and to maintain said outwardly extending portion in flexible engagement with said upper end of the tube.
